(57) **CLAIM**

The ornamental design for a bed for a magnetic resonance tomography diagnosis apparatus, as shown and described.

DESCRIPTION

FIG. 1 is a perspective view of a bed for a magnetic resonance tomography diagnosis apparatus showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a front elevational view where the side panel is in a raised position.
